LIFT TRUCK

George Quayle, Philadelphia, Pa., assignor to The
Yale & Towne Manufacturing Company, Stamford,
Conn., a corporation of Connecticut

Application July 25, 1940, Serial No. 347,466

19 Claims.

(Cl. 254—2)

This invention relates to a hand lift truck of the type in which the lifting mechanism is hydraulic. More particularly, my invention relates to a type of truck having a lifting head and a lifting platform, and with the lifting platform elevated relatively to the lifting head through the pressure thereagainst of the ram of a hydraulic mechanism.

In one modification of my invention, this hydraulic mechanism is actuated by the vertical swinging of the usual steering handle, it being a feature of my invention that the handle may operate the hydraulic mechanism in all steering positions thereof. In a second modification, I utilize a depressible pedal mechanism for operating the hydraulic mechanism, it being a feature of my invention that the hydraulic mechanism is so constructed that it is readily mounted between the lifting head and the lifting platform for lifting the said platform, while but slight change of certain parts of the truck are required to adapt the truck for pedal or handle operation.

A further feature of the invention is the particular mounting of the hydraulic mechanism, and the means whereby movement is transmitted therefrom to the lifting platform. More in detail, this feature of the invention utilizes mechanism whereby the platform may move relatively to the ram of the hydraulic mechanism without affecting the mounting or the operation of the ram. Those skilled in the art will appreciate the importance of this construction, since lifting platforms of the type described by me naturally do have some movement which it is undesirable should be transmitted to the hydraulic mechanism and the mounting means of the hydraulic mechanism.

I have attempted to set forth generally the more important features of my invention, but a reading of the specification which follows will indicate that there are a considerable number of additional features which are of great importance and which form valuable portions of my contribution to the art. These additional features, together with those already discussed, will of course be set forth in the claims hereinafter, it being further understood, moreover, that the patent claims which I expect to obtain should be of such a character as to prevent the utilization of my contribution to the art in specific forms other than those which I show and describe in this application.

For a description of my invention, I shall refer to the drawings wherein Fig. 1 is a plan view looking downwardly on my truck, with certain

parts cut away to better expose others of the parts. Fig. 2 is a side view of the truck of Fig. 1 with some of the parts cut away to better illustrate the operation of others of the parts. Fig. 3 is a view taken along lines 3—3 of Figs. 2 and 10. Fig. 4 is a perspective view of certain of the parts shown in Fig. 3. Figs. 5 and 6 are sections taken substantially along lines 5—5 and 6—6 of Fig. 3. Fig. 7 is a view of certain of the parts of Fig. 6 in another position. Figs. 8 and 9 are sections along lines 8—8 and 9—9 respectively of Fig. 6. Fig. 10 is a view along lines 10—10 of Fig. 3. Figs. 11 and 12 are enlarged views of parts of Fig. 10 in other operating positions. Fig. 13 is a view of the front of the truck of Figs. 1 and 2, showing that truck adapted for pedal operation. Fig. 14 is a horizontal section through the hydraulic mechanism of Fig. 13 illustrating the relation of the various portions of the hydraulic mechanism and the mounting of the foot treads. Fig. 15 is a view similar to Fig. 3 of the first modification and showing a modified form of hydraulic mechanism. Fig. 16 is a section taken along lines 16—16 of Fig. 14.

I shall now refer to Figs. 1 and 2 with reference to which I shall present an outline of my truck construction. Thereafter, the details thereof will be described with reference to the remaining figures as well as to Figs. 1 and 2. My truck comprises what I choose to call a lifting head 10, relatively to which is pivotally secured what I term a lifting platform 11, the lifting platform 11 having a front vertical standard 12 against which operates the thrust pin 13 of a hydraulic ram forming part of the hydraulic lifting assembly 14.

This hydraulic lifting assembly is actuated through means of a pivoting lever 15 by vertical swinging movement of the steering handle 16 connected to the lever 15 by a vertical strut 17. The steering handle 16 operates the lifting mechanism, and also steers the front steering wheels 18 of the truck, as will be understood by those skilled in the art. The rear wheels 19 of the truck are adapted for lifting movement relatively to the platform 11, whereby the rear end of the platform is elevated at the same time that the front end carrying the vertical standard 12 is elevated.

Referring now more particularly to Fig. 10, I shall first describe the lifting head 10 of my truck. This lifting head has mounted for rotation relatively thereto the wheel supporting forks 20, in which are mounted the front wheels 18 already described. The forks 20 form part of

what I term a steering head 21, which is rotatable relatively to the lifting head through means of the roller bearings 22 and the sleeve bearing 23. Pinned to the steering head 21 as at 24, and forming part of the steering head 21, is a collar 25, relatively to which is supported the lower main casting 16a of the steering and lifting handle 16 through means of the pin 27. A rod 28 extending from the steering handle casting 16a is pivoted at 29 to the collar 25 and forms part of the spring balancing mechanism for that handle, a construction which is not new in this application and need not be described therefore.

Formed as part of the handle casting 16a and movable integrally therewith is a pin 31, relatively to which is secured the strut 17 terminating in a ball 33 resting in a ball socket of the actuating pivoted lever 15, already described. The main portion of this lever 15 is substantially triangular in form, as can best be seen in Fig. 1, and has formed as part thereof a sleeve 34 whereby it is secured for rotation about a shaft 35 carried in bearings 36 formed in each of the two upwardly extending standards 37 of the lifting head 10, as is probably best seen in Figs. 2, 3 and 10.

The actuating lever 15 has formed also, as a portion thereof, an arm 38 which is forked at its end as at 39 and 40 for the mounting of a roller 41. This roller is utilized to actuate the pump of the hydraulic mechanism in a manner to be indicated later. It is obvious, of course, from the construction so far described, that the lifting and steering handle 16 is rotatable together with the steering head 21 to steer the truck, and that the handle 16 and its casting 16a may be swung vertically to operate the strut 17 to rotate the actuating lever 15 about the shaft 35, so as to force the roller 41 upwardly and downwardly to operate the pumping mechanism. It is further obvious to those skilled in the art that the strut 17 lies substantially in the axis of the steering head 21, and that through its ball end 33 operating in the ball socket of the actuating lever 15, the handle 16 may be utilized for lifting operation in any of its steering positions.

As is probably best seen in Figs. 2, 3 and 10, the lifting head has a downwardly and somewhat rearwardly extending portion 42 at each side thereof, within which are formed bearings for the mounting of a shaft 43. Right and left hand front lifting links 44 are adapted for mounting at the right hand and left hand ends of the shaft 43 just inwardly of the lifting head portions 42 for rotation on the said shaft. Each of these links has a bearing portion 45 (Fig. 5) whereby it is secured about a shaft 46 supported at each side of the lifting platform 11 at points near the front end of that platform, as is quite apparent from Figs. 2 and 10.

Referring now again to Fig. 5, each of the links 44 is shown as bifurcated at one end, forming bearings 47 for a pin 48, whereby each of the links 44 is pivotally secured to a threaded rod connector 49. Each of the rod connectors 49 is threaded for the entry of a rod 51 which is secured thereto in adjusted threaded relation by a locking nut 50. As is best seen in Fig. 2, each rod 51 extends to the rear of the truck where it is secured to a second rod connector 52 in the same manner as it is secured to connectors 49. Each of the rod connectors 52 is in turn secured through a shaft 53 relatively to forks 54 forming the bifurcated ends of rear wheel supporting links 55. The links 55 in turn are pivoted at 11a to

the platform frame 11 and support the rear load wheels 19.

It is now obvious that should the front vertical standard 12 of lifting platform 11 be moved vertically relatively to the lifting head 10, through the functioning of linkage and operating means not yet described, the shaft 46 on which are mounted the links 44 through their bearings 45, will cause the links 44 to rotate clockwise in Fig. 10 2 relatively to shaft 43 of the lifting head. This will cause the rods 51 to move to the right, thereby swinging the rear links 55 downwardly relatively to the lifting platform 11, effecting the movement of the lifting platform in a vertical direction to the position shown in dash and dot lines in Fig. 2.

In Fig. 2, the position of the vertical standard 12 in the elevated position of the platform is also shown in dash and dot lines. It will be noted that the effect of the movement of the wheels in Fig. 2 is to lengthen the wheel base of the truck, and as a matter of fact, there will be a tendency for the entire truck to move forward, as is illustrated by the dash and dot lines of the front 25 wheels 18 in Fig. 2. The advantage of the particular construction is that a load on the lifting platform will be moved away from the wall against which it may be stacked as the platform is elevated. The effectiveness of the construction will 30 be particularly clear to those skilled in the art.

For imparting lifting movement to the lifting platform 11, as just outlined, I utilize a hydraulic lifting assembly, which I have already indicated generally by reference numeral 14, and which 35 includes as part thereof a hydraulic ram having a rounded pin 13 for imparting lifting thrust to the vertical standard 12 of the lifting platform. This hydraulic lifting assembly, which is best shown generally in Figs. 3 and 10, has a 40 main base portion 57 from which extend ears 56 whereby the base portion, and therefore the entire hydraulic assembly, is secured for pivotal movement relatively to the shaft 43 already described as supported by the extensions 42 of the 45 lifting head 10. The base 57 extends upwardly and to each side to form a relatively large reservoir chamber 58 as defined by an outer wall 59.

Abutments formed within the chamber 58 of the base 57 are bored and threaded as at 60 and 61, there being secured relatively to the threads at 60 a sleeve-like member 62 forming the cylinder of the hydraulic pump of the hydraulic mechanism. Secured relatively to the threads 61, there is a sleeve-like member 63 forming the cylinder for a hydraulic ram 64, the ram being of any type well known in the art, and carrying a series of piston rings 65, as will be readily appreciated by those skilled in the art.

A pair of cover plates 66 and 67 are secured to the upper peripheral edge of the wall 59, whereby to completely enclose the reservoir 58, as best seen in Figs. 3 and 10. The cover plates 66 and 67 allow for the extension of the cylinders 62 and 63 therethrough, suitable sealing 65 means being provided for sealing the openings through which the cylinders protrude, all as will be understood by those skilled in the art.

Mounted within the cylinder 62 is a pump rod 68, to the upper end of which is pinned an actuating collar 69 carrying a cap 70 which in turn has a skirt 71 surrounding the upper end of the cylinder 62. The lower end of the pump rod 68 carries a piston and a suitable leather or other type sealing washer 72, whereby reciprocation

of the rod 68 will cause a pumping action within the cylinder, all as will appear clearly later.

A pair of telescoping compression springs 73 surround the pump rod 68 and lie between a washer 73a and the collar 69 whereby to urge pump rod 68 upwardly so as to bring the cap 70 against the pump actuating roller 41. The springs serve to press the cap against the roller 41, thereby pressing the roller 41 and the actuating lever 15 in a counter clockwise direction, as viewed in Fig. 10, and thereby bringing the ball socket of the actuating lever 15 against the ball end 33 of the strut 17 so as to take up any lost motion between the several parts, all as will be quite apparent.

The ram 64 carries at the upper end thereof the rounded pin 13, which has already been described, and which operates in a cooperating depression 14 formed within a block 75 which is secured as by welding or in any other manner, to parallel beams 76. The beams 76 have mounted between them and on each end thereof a roller 11 as best seen in Fig. 4, the rollers 11 in turn bearing against a plate 18 which is welded or otherwise secured to form an integral plate of the forward vertical standard 12 of the lifting platform.

Because of the particular mounting of the parts, it will be readily perceived that transverse movement of the vertical standard 12 relatively to the hydraulic mechanism will not in any way disturb the hydraulic mechanism, or tend to bend the shaft 43 on which the hydraulic assembly is supported through the ears 56, since the vertical standard will move freely transversely relatively to the two rollers 11. Moreover, any circular or twisting movement of the elevating standard 12, even if it should tend to rotate the beams 76 through rollers 11, will not be transferred to the hydraulic mechanism due to the relationship of the rounded pin 13 and the socket 14 of the block 75 carried by the beams 76. Naturally, longitudinal movement of the platform will simply cause a slight rotation of the entire hydraulic mechanism about the shaft 43, as is provided for by the mounting of the hydraulic mechanism. Actually, this motion is very slight since the linkage between the platform 11 and the lifting head is so calculated that the ram and the hydraulic assembly will move only that amount relatively to the lifting head which can be compensated for by the roller 41 operating against the cap 70 of pump rod 68.

There is of course a suitable stuffing box between the end of the hydraulic ram 64 and the cylinder 63 in which it is mounted, all as is well understood by those skilled in the art. For protecting the hydraulic ram, I employ a skirt 19 secured to the end of the ram through a cap 80, with the said skirt surrounding the outer wall of the cylinder 63. As the hydraulic ram moves vertically from Fig. 3 to lift the platform, it is of course obvious that the skirt 19 will maintain covered the end of the ram at all times, thereby protecting it against picking up abrasive material and carrying it back into the cylinder 63. The skirt 11 of cap 70 of the pump rod 68 has a like function.

There was described earlier the linkage whereby the lower end of the platform 11 is mounted relatively to the lifting head 10. It will now be well to indicate that the upper end of the vertical standard 12 of the lifting platform is also secured by linkage to the lifting head 10. Thus, welded

or otherwise secured to vertical standard 12 are spaced plates 81, between which is supported a shaft 82 (Figs. 1 and 10). A substantially H-shaped lever 83, best shown in Fig. 1, is equipped 5 with a sleeve portion 84 at one end thereof whereby it is secured about the shaft 82. At its other end, the H-shaped lever 83 has formed thereon a sleeve portion 85 whereby it is secured relatively to a shaft 86 carried in bearings 86a at 10 the upper end 37 of the lifting head 10. It is the function of the lever 83 to guide the upper end of the vertical standard 12 in its movement relatively to the lifting head, just as the lower links 44 guide the lower end of the standard and the 15 platform 11 in their elevating movement.

Referring now to Figs. 3, 5 and 6, I shall describe the various passages formed within the base 57 of the hydraulic mechanism, and the valves positioned relatively to those passages 20 whereby the operation of the hydraulic mechanism will be understood. A longitudinally extending main valve bore 87, 88 is formed in the base 57 inclined somewhat relatively to the horizontal, as best shown in Fig. 6. This main valve bore includes a bore 87 and a further bore 88, the two bores being coaxial. The valve bore 87, 88 is closed at one end through the screw threaded cap 89 holding in place the gasket 90, all as is best seen in Figs. 3 and 6. The opposite end is 30 closed by a threaded plug 105.

Mounted within the bore 87 is a valve 91 having a series of holes 92 drilled therethrough, as is best illustrated in section in Fig. 9. This valve is formed to cooperate with a seat 93 at the left 35 hand end of the bore 87. A plug 94 is mounted within the bore 88, and itself has a bore 95 therethrough forming a valve passage for cooperation with a valve 96. The valve 96 is seated relatively to a valve seat 97 formed on the plug 94, and is held against this seat by a spring 98, as is 40 readily seen. A spring 99 lies between the plug 94 and the valve 91 to maintain the valve 91 normally against its seat 93.

A passage 100 leads through base 57 into the 45 valve bore 87 from the reservoir chamber 58, while a bore 101 leads to the valve bore 88 from the pump cylinder 62, as can be seen by reference to Figs. 3, 5 and 6, the bore 101 communicating with the cylinder 62 through the bore 102. Through bores 103 and 104, communication 50 is established between the ram cylinder 63 and the extreme left hand end of the main valve bore which is to the left of the valve 96. Thus, it may be said that in Fig. 6 the right end of 55 valve bore 87, 88 communicates with the reservoir, the central portion communicates with the pump, and the left end communicates with the ram.

The operation of the several valves and passages so far described will now be explained. 60 Upon upward movement of the pump rod 68 and its piston, pressure against the end of the valve 91 will naturally be relieved, whereby to move it away from its seat at 93 against the force of spring 99 so that fluid will flow from the passage 100 through the holes 92 of the stem of valve 91 and through the passages 101, 102 into the pump. At the beginning of the downward pumping stroke, the valve 91 will become seated at 93, and all of the pump pressure will be introduced 65 against the end of the valve 96. This will unseat valve 96 relatively to its seat at 97 and against the resistance of spring 98, whereby to force the fluid through the passages 104 and 103 into the 70 cam cylinder 63, whereby to move the ram 64 against the pressure of the pump.

vertically to lift the platform. Through a series of strokes, the ram will be moved to its completely elevated position.

If now it is desired to lower the load, utilization is made of a cam operating shaft 106 and its cam surface 107. It will be noted that the cam operating shaft 106 is mounted within a transverse bore 108 formed in the base 57, as best illustrated in Figs. 5 and 6, the shaft extending outwardly of the base 57 through a suitable stuffing box 109. There will be described later the mechanisms which are mounted on the shaft 106 for operating that shaft and for controlling its movement. Suffice it to say at this time that when the shaft 106 is rotated in a counter clockwise direction to position F, as seen in Fig. 6, its surface 107 will move the valve 96 off its seat at 93, so as to establish low pressure communication between the pump and the reservoir 58 through passages 100, 101, 102. Thereafter, up and down movement of the pump will have no affect whatsoever on the pumping mechanism, since it will be impossible to generate sufficient pressure to move the valve 96 off its seat at 93, as is necessary when it is desired to admit fluid under pressure to the hydraulic ram. In this position of the parts, there will be had what is known in the art as a free operating handle, and which is obtained usually in mechanical structures by simply releasing the operating mechanism from the vertically swinging handle.

If in the position of the parts described, it is desired to lower the truck platform 11, rod 106 is rotated further carrying cam surface 107 past the position of Fig. 7 to the position L shown in Fig. 6. This rotation of rod 106 will bring the left hand end of the valve 96 against the right hand end of the valve 96, moving that valve off its seat at 93. Communication will then be established between the ram and the reservoir 58 through the valve passage 95, the open valve seat 93, and the bores of valve 96 whereby to effect the lowering of the load platform.

Those skilled in the art will fully appreciate that the initial withdrawal of the valve 96 from its seat at 93, especially with a heavy load on the ram, will cause an extremely swift movement of a small quantity of fluid past the valve seat 93. This extremely swift movement of fluid will gradually wear away the valve seat under the usual operating conditions. Therefore, I have arranged means whereby there is substantially no flow of fluid past the valve seat 93 until the valve 96 has been moved off its seat a sufficient distance to present a relatively large opening. The flow of fluid is then in relatively large volume, and as will be understood by those skilled in the art, the speed of the flow of the fluid will be considerably reduced.

As is best shown in Figs. 6, 7 and 8, the valve plug 94 is counter bored at 94a to present a somewhat larger flow opening than the remainder of valve bore 95. The valve stem of valve 96 has a necked portion 96a which is normally opposite counter bore 94a and is defined at one end by a shouldered portion 110 which, in the normal position of the parts in Fig. 6, fully closes the bore 95 within which the valve 96 is adapted to slide. Extending from this surface 110 in valve 96 is a gradually tapered groove 111, shown in section in Fig. 8, the groove 111 being entirely eliminated at the shouldered surface 110.

Because of this relation of the parts, it is readily seen that even if the valve 96 is moved off its seat 93 toward the position of Fig. 7, there still

will be very little flow past the seat 93 because the surface 110 of the valve maintains substantially closed the valve bore 95. It is only after the valve 96 has been moved for a considerable distance, and somewhat further than shown in Fig. 7, whereby to space it from its seat 93 an appreciable amount, that the surface 110 is moved sufficiently out of the main portion of the bore 95 and opposite the counterbore 94a to expose part of the groove 111 of the valve stem. An appreciable amount of fluid may then begin its flow past the valve seat 93, and at a speed which is comparatively low, so that the worst possible wear condition no longer exists. It is well to indicate that the groove 111 acts to control the platform lowering speed, that speed being increased as the valve 96 is moved to the left in Figs. 6 and 7 to expose the deeper portion of the groove to the fluid.

20 Referring now once again especially to Figs. 3, 5, 11 and 12, the end of the valve control rod 106 has secured thereto the foot treadle 115 through its sleeve portion 116 and cotter pin 116a, whereby the treadle will rotate the rod 106 to control the valve mechanism, as previously described.

25 Rotating with the treadle 115 and its sleeve 116 are a pair of ears 117 carrying a pin 118. Mounted on this pin 118 through bifurcated legs 119 is a cam piece 120. This cam piece 120 has secured thereto a rod 121 which slides at its upper end in holes 122 formed in the cover plates 66 and 67 of the reservoir 58. A spring 123 surrounds the rod 121 and bears between the lower cover 30 plate 67 and the upper surface of the cam 120, whereby through the pin 118, it tends to rotate the treadle in a clockwise direction, looking at Figs. 11, 12 and 13, and to maintain the valve control rod 106 in its full line position of Fig. 6. 35 In this position of the parts, lifting movement of the hydraulic mechanism will be effected by the pumping action of the steering handle 16.

40 Movably also integrally with the treadle 115 is the roller 125 which, in the normal position of the parts, that is, in the position of Figs. 5, 6 and 10, lies within a depression or cam surface 126 formed on the cam piece 120. It will of course be appreciated that the relation of the roller and cam surface may easily be reversed and that other cooperating parts may be used. With the truck platform in any particular elevated position, should it be desired to obtain a free handle by the moving of the valve control rod 106 and its cam surface 107 to the position F in Fig. 6, 45 as already described, the operator steps on the treadle 115 and moves that treadle from the position of Fig. 10 to the position of Fig. 11 against the resistance of spring 123, whereby to move the roller 125 out of the depression or cam surface 126 to the position of Fig. 11. In this position of the parts, the spring 123 will tend, of course, to rotate the roller 125 and the treadle 115 back to the position of Fig. 10 but the surface 127 cooperating with the roller will prevent such movement.

50 If, in this position of the parts, it is now desired to rotate the valve control rod 106 to the position L in Fig. 6, whereby to release the load by the movement of the valve stem 96 off its seat 93 as in Fig. 7, the operator will move the pedal 115 to the position of Fig. 12, thereby compressing the spring 123 even more than previously. Naturally, in this position of the parts, the ram and platform 11 will be lowered and the fluid will be moved back into the reservoir.

The operator now has a choice of two actions. If he wishes to have a free handle so that the truck may be hauled about, he may return the treadle slowly to the position of Fig. 11 where it is stopped by roller 125 striking surface 127. In this position of pedal 115, the valve 81 will be maintained off its seat at 93 and free communication is had between the pump and reservoir to yield the free handle desired. On the other hand, if the operator wishes to place the valve mechanism in its initial position of Fig. 6 so that operation of the lifting handle will elevate the truck platform, he has only to release the treadle in the position of Fig. 12 to allow the full action of the spring 123. The spring 123 will, in its then state of compression, rotate the treadle 115 rather swiftly towards the position of Fig. 11. The speed of movement is such that the surface 127 will be incapable of preventing the movement of the roller 125 back into the depression 126, as shown in full lines in Fig. 10. Therefore, the treadle will return to its initial position of Fig. 10, all as is quite apparent.

Also mounted for movement with the treadle 115 is a cam 128, the purpose of which will now be described. Referring also to Figs. 3, 5 and 10, it will be noted that the left hand front lifting link 44 has mounted thereon an adjustable screw bolt 129. It is the function of this bolt when the platform is in a fully elevated or other predetermined position, to strike the cam 128 so as to move the treadle from its position of Fig. 10 to the position of Fig. 11. The purpose of this action is to present a free handle immediately upon the elevation of the load platform to a predetermined position. This predetermined position may be varied, of course, by an adjustment of the bolt 129, all as is quite apparent.

Referring now to Figs. 13, 14 and 15, I show there certain modifications of my structures already described. The first modification includes means whereby a foot operated treadle 130 is adapted to operate the pump mechanism. Instead of utilizing the type of actuating lever 15 shown in Fig. 10, I utilize a short form of lever, designated by reference numeral 15a, pivoted on shaft 35a in a manner similar to the pivoting of the lever 15 on the shaft 35 carried by the portion 37 of the lifting head 10 in the first modification.

It will be recalled that the actuating lever 15 of the first modification has extending therefrom but a single lever arm 38, on which is mounted the roller 41. In the modification of Figs. 13, 14 and 15, the lever 15a has two extending arms, designated in the drawings by reference numeral 38a, but only one of these arms is bifurcated for the mounting of a roller 41a for operating the pump piston, as best shown in Figs. 13 and 15.

Each of the arms 38a carries a short shaft 131 whereby connection is made to vertical struts 132, which at their lower ends are pivoted at 133 to the foot treadles 130. The roller 41a is mounted on the shaft 131 carried by the right arm 38a in Fig. 15. As is apparent from Fig. 14, the foot treadles 130 are mounted at each side of the lifting head, and are connected by a transverse bar 131 so that the pump may be actuated from the right or left hand of the truck, depending on which is most convenient in any particular position of the truck.

The foot treadles 130 are mounted for pivoting movement about a shaft 43a, which is positioned exactly as is the shaft 43 of the first modification. By comparing Figs. 3 and 15, it will be seen that shaft 43a is simply slightly longer

than shaft 43 in order to support thereon the treadles 130, which treadles are of course not required in the modification of Fig. 3. The shaft 43a, just as does the shaft 43, supports the links 44 and the base 57 of the hydraulic mechanism through the ears 56 thereof.

A further variation from the modification of Fig. 3 is in the securing of spring brackets 134 to the side extensions 42 of the lifting head. 10 These spring brackets 134 support the ends of springs 135, which at their other ends are secured at 136 to the treadles 130 whereby to somewhat balance the weight of those treadles, thereby assisting the springs 73 of the pump rod in 15 maintaining the treadles in their normal position.

The hydraulic mechanism shown in Figs. 14, 15 and 16 is modified by the addition of means whereby when the platform is lightly loaded, or 20 not loaded at all, the pumping action will cause a swift elevating movement thereof, while when the platform becomes loaded, the lifting motion thereof will be at a slower rate. In order to accomplish this, the ram mounted within the cylinder 63 and designated by reference numeral 137, is bored as at 138 for the mounting therein of a stationary ram utilizing a piston 139 secured to a sleeve-like rod 140. Rod 140 is threaded as 25 at 141 into the base 57 of the hydraulic mechanism and communicates with passages 103, 104 leading to the main valve bore 87, 88 described with reference to the first modification. In the 30 lowered position of the platform, there is preferably a space 142 between the piston 139 of the stationary ram and the block 143 forming the 35 end of the movable ram 137.

As best seen in Figs. 14 and 16, the lower end of the cylinder 63 in which operates the large 40 movable ram 137, is in communication through a series of holes 145 with a valve passage 146. This passage 146 is in communication with a bore 147, which in turn is in communication with the reservoir 58. The passage 103 whereby fluid 45 is supplied to the stationary and movable rams, communicates through a small opening 148 with the valve passage 146.

Through suitable means which are shown in Fig. 16 and require no description, there is mounted within the valve passage 146, a valve 149, which is spring pressed by a spring 150 off its 50 seat at 151 and in position to maintain closed the opening 148. Communication between the cylinder 63 of the large ram and the reservoir 58 through the three holes 145 is normally maintained when valve 149 is in its position of Fig. 16. 55 In the position of the parts in Figs. 15 and 16, fluid from the pump is first introduced through the bore 104 into the bore 103 and passes up through the tube 140 into the space 142 between the piston 139 of the small ram and the cap 143 60 of the large ram, whereby to move the large ram relatively to the small stationary ram. This movement will of course move the large ram relatively to the small stationary ram. This movement will of course move the large ram relatively to its cylinder 63, whereupon fluid fills 65 the resulting space in the bottom of cylinder 63, flowing from the reservoir 58 through the hole 147, past the valve seat 151, and through the several holes 145.

70 When the load is encountered, or if the load is very heavy, it will be realized that the pressure will be greatly increased and will overcome the pressure of spring 150 holding valve 149 against opening 148 whereby to move the valve 149 from

opening 148. As soon as any slight opening occurs at 148, the fluid will then exert pressure against the relatively large surface 149a of the valve 149, and will quickly move that valve into its dotted line position of Fig. 16, in which position it becomes seated against seat 151, shutting off communication between the reservoir 58 and the cylinder 63. Fluid then flows from the pump through the small opening 148 and the bores 145 into the cylinder 63 to actuate the large ram.

Summarizing the action of the last modification, it is quite apparent that upon operating movement of the pump, fluid will flow under the control of valves in main valve bore 87, 88 through passages 104 and 103, and up through the tube 140 to separate the large ram from the small stationary ram. As soon as the pressure is developed through the lifting platform 11 encountering the load or through an increase of the load, the valve 149 will be moved within the valve passage 146 to open up communication at 148, 146 and 145 between the pump and the large ram, whereupon the large ram will be moved at a slow rate so that it may handle the relatively large load involved.

In the modification of Figs. 14, 15 and 16, it will be appreciated that the valve mechanism whereby the change from the high speed to the low speed operation is made possible, is entirely automatic, and that this mechanism does not in any way affect the operation of the control mechanism of Figs. 5 and 6 described earlier. It will be well also to indicate that in Fig. 14, there is shown the relation of the several valve mechanisms of Figs. 5 and 6 to the pump and the ram, and that this relationship of the parts in the modification is the same as in the first structure described herein. The only change in Fig. 14 is the addition of the valve mechanism shown in Fig. 16, but as has already been said, this does not affect the operation of the main valve mechanism in any way. It will also be well to indicate that the main valve mechanism is operated by the foot treadle 115 in the modification of Fig. 14 in the same manner as in the first structure described.

I should like to emphasize further at this point that a basic feature of my invention is the arrangement of the parts thereof whereby foot or hand operation may be obtained with a minimum of change, and with the main elements of my combination remaining unchanged. This is in great part due to my utilization of a hydraulic assembly in which the pump, as well as the ram, is merely in thrust engagement with the parts cooperating therewith. This feature makes it possible to arrange for the mounting of the pump actuating means entirely on the lifting head, all as will be appreciated. It is thought that a further analysis and description of my invention is not necessary, especially since reference to the claims will further clarify the significance and value of various cooperating parts thereof.

I now claim:

1. In a truck of the class described, a lifting head, an elevating platform, a hydraulic lifting assembly pivoted at its lower end to said lifting head and including a ram bearing at its upper end against said platform, a rotating steering head in said lifting head, a steering handle secured to said steering head for rotating the same while mounted for vertical swinging movement relatively to said head, a pump included in said hydraulic lifting assembly and comprising a plunger, a lever pivoted on said lifting head, a roller through which said lever bears at one end against said pump plunger to allow for movement between said plunger and said lever 5 as the platform is elevated, the other end of said lever extending to a point over the axis of said steering head, and means securing the said other end of said lever to said steering handle whereby vertical swinging movement of said steering handle moves said pivoted lever to actuate the pump plunger.
2. In a truck of the class described, a lifting head, an elevating platform, a hydraulic lifting assembly pivoted at its lower end to said lifting head and including a ram bearing at its upper end against said platform, a rotating steering head in said lifting head, a steering handle secured to said steering head for rotating the same while mounted for vertical swinging movement 15 relatively to said head, a pump included in said hydraulic lifting assembly and comprising a plunger, a lever pivoted on said lifting head and bearing at one end against said pump plunger, and a universal joint connection between the other end of said lever and said steering handle 20 whereby vertical swinging movement of said steering handle in all steering positions thereof moves said pivoted lever to actuate the pump plunger.
3. In a truck of the class described, a lifting head, an elevating platform, a hydraulic lifting assembly pivoted at its lower end to said lifting head and including a ram bearing at its upper end against said platform, a rotating steering head in said lifting head, a steering handle secured to said steering head for rotating the same while mounted for vertical swinging movement 25 relatively to said head, a pump included in said hydraulic lifting assembly and comprising a plunger, a lever pivoted on said lifting head and bearing at one end against said pump plunger, the other end of said lever extending substantially over the axis of the steering head, and a vertical strut member bearing at its upper end against said end of the said lever and at its lower end against the steering handle, and movable substantially in the steering axis by vertical 30 swinging movement of said steering handle in all steering positions thereof to move said pivoted lever whereby to actuate said pump.
4. In a truck of the class described, a lifting head, an elevating platform mounted for lifting movement relatively to said lifting head, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included in said hydraulic lifting assembly 35 comprising a plunger, a lever pivoted on said lifting head having a part bearing against a surface of said pump plunger whereby to allow for movement between said plunger and the lever as the hydraulic assembly moves on its pivot when the platform is being elevated, and means for moving said lever to actuate the plunger.
5. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 40
6. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 45
7. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 50
8. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 55
9. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 60
10. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 65
11. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 70
12. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included 75

in said hydraulic lifting assembly comprising a plunger, a lever pivoted on said lifting head, a roller mounted at one end of said lever and bearing against the upper end of said pump plunger whereby to allow for movement between the plunger and the lever as the platform is elevated, means for moving said lever to actuate the plunger through the intermediary of said roller, and means mounting said platform relatively to said lifting head whereby the hydraulic lifting assembly extending between said head and platform receives but slight pivotal movement while elevating said platform.

6. In a truck of the class described, a lifting head, an elevating platform, a hydraulic lifting assembly, means pivoting said assembly at its lower end to said lifting head, a ram extending from said assembly and bearing at its upper end against said platform whereby to impart lifting movement to said platform and to control lowering movement of said platform, a pump included in said hydraulic lifting assembly comprising a plunger, a lever pivoted on said lifting head, and bearing at one end against said pump plunger in all positions thereof, means for moving said lever to operate the plunger, and means mounting said platform for elevating movement relatively to said lifting head in substantially a predetermined line whereby the hydraulic lifting assembly extending between said head and platform receives but slight pivotal movement while elevating said platform.

7. In a truck of the class described, a lifting head, an elevating platform, a hydraulic lifting assembly, means pivoting said assembly at its lower end to said lifting head, a ram extending substantially vertically from said assembly and bearing at its upper end against said platform whereby to apply lifting effort to said platform and to control lowering movement of said platform, a pump included in said hydraulic lifting assembly comprising a plunger extending parallel to said ram, a lever pivoted on said lifting head and bearing against said pump plunger for operating said pump plunger in all positions thereof as the hydraulic assembly moves on its pivot while the platform is being elevated, means for moving said lever to operate the plunger, and means mounting said platform for elevating movement relatively to said lifting head in substantially a predetermined line whereby the hydraulic lifting assembly extending between said head and platform receives but slight pivotal movement while elevating said platform.

8. In a truck of the class described, a lifting head, an elevating platform pivoted to said lifting head, a hydraulic lifting assembly including a ram, means whereby said assembly is supported at its lower end on said lifting head for pivotal movement in a vertical plane longitudinal of the said truck, a thrust accepting means for said elevating platform against which the ram bears to lift the platform relatively to said lifting head, and means whereby said thrust accepting means are adapted for movement transversely relatively to said platform while imparting thrust thereto from said ram.

9. In a truck of the class described, a lifting head, an elevating platform pivoted to said lifting head, a hydraulic lifting assembly including a ram, bearing means whereby said assembly is supported at its lower end on said lifting head for free pivotal movement relatively to said lifting head, thrust accepting means carried by said elevating platform, a thrust member carried on

the upper end of said ram and bearing in a cooperating depression of said thrust accepting means to lift the platform, the cooperation between said thrust member and said thrust accepting means maintaining said hydraulic assembly particularly positioned on said bearing means as said elevating platform moves relatively to said lifting head during the elevating movement thereof.

10. In a truck of the class described, a lifting head, an elevating platform pivoted to said lifting head, a hydraulic lifting assembly including a ram, means whereby said assembly is supported at its lower end on said lifting head for pivotal movement in a vertical plane longitudinal of the said truck, a thrust accepting assembly for said platform including a transverse beam against the central portion of which the ram bears, and a roller at each end of said beam bearing against a surface of said platform, whereby said platform may move transversely relatively to said beam on said rollers while accepting thrust therefrom through said rollers.

11. In a truck of the class described, a lifting head, an elevating platform pivoted to said lifting head, a hydraulic lifting assembly including a ram supported at its lower end on said lifting head, a thrust accepting assembly for said platform including a beam against the central portion of which the ram bears, and a roller at each end of said beam bearing against a surface of said platform, whereby said platform may move relatively to said beam on said rollers while accepting thrust therefrom through said rollers.

12. In a truck of the class described, a lifting head, an elevating platform pivoted to said lifting head, a hydraulic lifting assembly including a ram, means whereby said assembly is supported at its lower end on said lifting head for pivotal movement in a vertical plane longitudinal of the said truck, a thrust accepting assembly for said platform including a transverse beam against the central portion of which the ram is adapted to bear, a roller at each end of said beam bearing against a cooperating surface of said platform, whereby said platform may move transversely relatively to said beam on said rollers while accepting thrust therefrom through said rollers, and means between said ram and said beam in rotatable thrust engagement whereby to permit rotation of said beam relatively to said ram.

13. In a truck of the class described, an elevating platform, lift thrust imparting means, a lift thrust accepting assembly for said platform including a transverse beam, a roller at each end of said beam, and a surface on said platform resting on said rollers whereby said platform is movable relatively to said beam on said rollers.

14. In a truck of the class described having a lifting head and a lifting platform, a hydraulic ram assembly including a base casting, bearing means formed on said casting and whereby it is pivotally secured to said lifting head, a sleeve-like cylinder threaded in to said base casting, a reservoir chamber formed in said base casting and extending about the lower portion of said cylinder, a cover plate for said reservoir having an opening through which the upper portion of said cylinder extends, a ram in said cylinder bearing at its upper end and against said platform whereby to impart lifting movement to said platform, and pump means in said assembly for applying fluid under pressure to said cylinder whereby to impart movement to said ram.

15. In a truck of the class described, a lifting head, a steering head rotatable relatively to the front end of said head and carrying wheels for supporting said lifting head, a vertically extending standard forming the rear of said lifting head, a load platform having a vertically extending standard, a link pivoted at its front end to the upper end of said lifting head standard and pivoted at its rear end near the upper end of said platform standard, a transverse shaft supported on the lower end of said lifting head standard, a link pivoted at its front end on said shaft and pivoted rearwardly thereof at substantially the lower end of said platform standard, a hydraulic lift assembly comprising a base carrying the usual reservoir, ram and pump, bearing means on said base whereby it is pivotally supported on said transverse shaft and with the upper end of the ram of said assembly bearing against the said vertical platform standard, a pump actuating lever pivoted on the vertical standard of said lifting head, and vertically swinging means connected to said lever for moving it to operate said pump.

16. In a truck of the class described, a lifting head, a steering head rotatable relatively to the front end of said head and carrying wheels for supporting said lifting head, a vertically extending standard forming the rear of said lifting head, a load platform having a vertically extending standard, a link pivoted at its front end to the upper end of said lifting head standard and pivoted at its rear end near the upper end of said platform standard, a transverse shaft supported on the lower end of said lifting head standard, a link pivoted at its front end on said shaft and pivoted rearwardly thereof at substantially the lower end of said platform standard, a hydraulic lift assembly comprising a base carrying the usual reservoir, ram and pump, bearing means on said base whereby it is pivotally supported on said transverse shaft and with the upper end of the ram of said assembly bearing against the said vertical platform standard, a pump actuating lever pivoted on the vertical standard of said lifting head, and a vertically swinging pedal pivoted on said transverse shaft and connected to said lever for moving it to operate said pump.

17. In a truck of the class described, a lifting head having a vertical standard, a steering head supporting said lifting head, a steering handle mounted on said steering head for vertical swinging movement, an elevating platform having a standard and pivotally connected through upper and lower links to said lifting head standard, a hydraulic lift unit pivoted at its lower end to said lifting head and extending vertically between said standards, a ram forming part of said

lift unit and bearing with its upper end against the standard of said elevating platform whereby to lift said platform on said upper and lower links relatively to said lifting head, a pump plunger forming part of said hydraulic lift unit, a lever pivoted on said lifting head standard and having one end bearing directly against said pump plunger in all positions thereof, for operating said pump in all positions of said lift unit

5 10 15 20 25 30 35 40 45 50 55

as said elevating platform is lifted, and a vertical strut for connecting the other end of said lever to said steering handle whereby vertical swinging of said handle actuates said pump plunger.

18. In a truck of the class described, a lifting head having a vertical standard, a steering head supporting said lifting head, a steering handle mounted on said steering head for vertical swinging movement, an elevating platform having a

standard and pivotally connected through upper and lower links to said lifting head standard, a hydraulic lift unit pivoted at its lower end to said lifting head and extending vertically between said standards, a ram forming part of said lift unit and bearing with its upper end against the standard of said elevating platform whereby to lift said platform on said upper and lower links relatively to said lifting head, a pump plunger forming part of said hydraulic lift unit, a lever pivoted on said lifting head standard and having one end bearing directly against said pump plunger in all positions thereof, for operating said pump in all positions of said lift unit as said elevating platform is lifted, and means connecting the said lever to said steering handle whereby vertical swinging of said handle actuates said pump plunger.

19. In a truck of the class described, a lifting head having a vertical standard, an elevating platform having a standard and pivotally connected through upper and lower links to said lifting head standard, a hydraulic lift unit pivoted at its lower end to said lifting head and extending vertically between said standards, a ram forming part of said lift unit and bearing with its upper end against the standard of said elevating platform whereby to lift said platform on said upper and lower links relatively to said lifting head, a pump plunger forming part of said hydraulic lift unit, a lever pivoted on said lifting head standard and having one end bearing directly against said pump plunger in all positions thereof, for operating said pump in all positions of said lift unit as said elevating platform is lifted, and means connecting the said lever to said steering handle whereby vertical swinging of said handle actuates said pump plunger.

40 45 50 55

19. In a truck of the class described, a lifting head having a vertical standard, an elevating platform having a standard and pivotally connected through upper and lower links to said lifting head standard, a hydraulic lift unit pivoted at its lower end to said lifting head and extending vertically between said standards, a ram forming part of said lift unit and bearing with its upper end against the standard of said elevating platform whereby to lift said platform on said upper and lower links relatively to said lifting head, a pump plunger forming part of said hydraulic lift unit, a lever pivoted on said lifting head standard and having one end bearing directly against said pump plunger in all positions thereof, for operating said pump in all positions of said lift unit as said elevating platform is lifted, and means connected to the said lever for moving it to actuate said pump plunger.

GEORGE QUAYLE.
